CENTRIFUGAL CASTING MACHINE

Karl F. Dailey, Cleveland, Ohio

Application February 17, 1934, Serial No. 711,801

14 Claims.

(Cl. 22—65)

This invention relates to means for centrifugally casting steel ingots or the like, and having rotatably mounted mold means with a plurality of cavities to be simultaneously poured from a corresponding plurality of rotating spouts. Apparatus for the purpose is illustrated and described in my copending application, Serial No. 680,564, filed July 15, 1933, and the objects of this invention are generally to improve upon what is there disclosed.

Where such simultaneous pouring is to be had it becomes highly important that pouring be equal in all of the mold cavities, which are preferably of identical capacity, and that the equalization be as nearly automatic as possible; and the provision for such equalization is a particular object of this invention.

The invention contemplates pouring during rotation of both mold and spout elements from a relatively stationary main ladle which, however, may be moved between a plurality of casting machines to serve all of the latter in succession. The main ladle may pour directly into the spout means or serve the latter by way of an auxiliary ladle or tundish as will appear. That the spout means may serve as many molds as the main ladle serves, the invention includes, as a further object, an arrangement whereby a single spout means unit may be employed; and where an auxiliary ladle is employed the invention includes means for moving such auxiliary ladle also between casting machines.

Another important object of the invention is to provide means for compacting the casting before complete solidification, at its inner radial part, by mechanical means, whereby the density of the casting may be made more uniform and occlusions and the like will be better segregated as a scrap crop part of the casting.

The exact nature of the invention together with further objects and advantages thereof will be apparent from the following description taken in connection with the accompanying drawings, all of which illustrate more or less conventionally various embodiments of the invention as will appear, together with pertinent associated parts. More particularly Fig. 1 is a typical sectional elevation illustrative of one form of the invention; Fig. 2 is a detail in plan view of the adjacent parts of a spout arrangement taken as in the plane of line 2—2, Fig. 1; Fig. 3 is a detail in vertical section as in the plane of line 3—3, Figs. 1 and 2; Fig. 4 is a view similar to Fig. 1 but illustrating modifications as will appear; Fig. 5 is a layout in sectional elevation illustrat-

ing the manner of employment of the invention as shown in Fig. 4; Fig. 6 is an enlarged sectional detail of mold parts of a modified section illustrating the manner of protection at the mouth of the mold cavity and other features; Fig. 7 is a top plan view of Fig. 4, illustrating apparatus for compression of the castings before solidification; Fig. 8 is an enlarged vertical section illustrating a modified spout and ladle arrangement; Fig. 9 is an enlarged detail similar to Fig. 8 but showing another modification of the same; Fig. 10 is a section as in the plane of line 10—10, Fig. 9; Fig. 11 is a plan view of the spout parts illustrated in Fig. 9; and Fig. 12 is an enlarged section of a slightly modified form of the mold of Fig. 1.

With reference now to the drawings and first to Figs. 1—3 thereof, 1 indicates generally a table mounted for rotation about an upright axis by suitable driving means not shown but acting through the pair of gears indicated at 2. Suitably secured upon the table is a stack of three mold sections 3, 4 and 5 providing a pair of similar mold cavities 6 and 7 each concentric about the axis of rotation of the table 1.

The mold sections are adjustably secured in their stacked relation by means permitting controlled relative movement therebetween during shrinkage of the castings in cooling; such means including posts 8 spaced about the periphery of the machine, each having a clamping head member 9 bearing against the uppermost mold section 5 to bear it against a stop 10 fixed on the base table 1, and swiveled or removable to permit removal of the mold section 5. A second series of posts similar to the posts 8 but associated with the intermediate mold sections 4, is provided for controlling its motion under contraction.

The two sets of mold-section-controlling posts are simultaneously adjustable by controlling means here generally indicated at 11; the arrangement being such that during rotation of the mold sections they may be permitted to separate, the intermediate section 4 from the lowermost section 3, and the uppermost section 5 as much from the intermediate section 4, yet such section motion being limited by adjustment of the mechanism including the parts indicated at 11. An arrangement for a similar purpose is more fully illustrated and described in my said copending application.

Each major mold cavity has an annular port 12 opening generally inwardly or toward the axis of rotation, and as here shown directed upwardly as well.

A pair of spouts are provided, one for each mold cavity, each arranged to deliver into the port 12 of its mold cavity. There being two mold cavities here illustrated, there need only be the two spouts 13 indicated; although it will be apparent that more mold cavities might be provided with a corresponding spout for each, or there might be more than one spout for each cavity. The spouts are preferably located symmetrically about the axis of rotation and where but two are employed, they may be located opposite each other as illustrated.

Each spout has an enlarged base part 14 located adjacent the axis of rotation, with a trough part 15 leading radially outwardly therefrom to deliver into its port 12. The base parts 14 of the spouts extend about the axis of rotation as indicated in Fig. 2, and one is located above the other as indicated in Fig. 1, so that together they provide a cavity extending entirely about the axis, each subtending an equal angle relative thereto. Each spout is thus generally of Y form. The trough parts 15 of the spouts are preferably slightly tilted as indicated in Fig. 3, in the direction of spout rotation, which will be described. The spouts are mounted upon a part 17 preferably movable radially thereon as by the links 16, whereby the mouths of the spouts, which may have nozzle parts 18, may have adjustment outwardly to a feeding relation relative to their ports 12, and therefrom inwardly to positions clearing the mold sections. The spouts are illustrated in Figs. 1 and 2 as in their outer or pouring position.

35 The spouts then, together with the part 17 on which they are mounted, comprise a unit. That this unit may be driven about the axis of revolution of the mold, at speed variable independent of the mold, a sleeve 19 is provided with a head 20 on which the part 17 bears, and gearing indicated at 21 is arranged to provide a drive for the sleeve from a suitable power source not shown. Means removably interassociating the part 17 with the head 20 are provided, here conventionally indicated as including the centering flange 22 fitting about the head 20, which is circular, and the lugs 23 on the part 17 fitting in suitable openings in the head.

A ladle A having a central discharge opening a 50 is provided for supplying the molten metal to the casting machine.

In the modification here illustrated, an auxiliary ladle 24 is arranged to receive from the outlet a of the main ladle and to discharge into the spouts 13; the spout assembly, including an auxiliary ladle when one is used, may be moved independently of the ladle or both the spout assembly unit and the auxiliary ladle 24 may be associated with the main ladle A to be movable therewith to serve a number of casting machines. To this end bracket means 25 is secured on the main ladle A having flange means 26 in supporting relation with flange means 27 on the auxiliary ladle 24, and having flange means 28 in similar relation with flange means 29 provided on the part 17 of the spout unit; these flange means being generally annular or at least sufficiently so, about the axis of rotation, to permit free rotation of the spout unit and of the auxiliary ladle relative to the main ladle A, when the main ladle A is in pouring position as indicated; and the arrangement being such that when the main ladle A is raised from the pouring position, it will carry with it the spout unit and auxiliary ladle.

75 Obviously the spout unit when in pouring po-

sition will rest upon its driving head 20. For adjustable support of the auxiliary ladle in pouring position, it is provided with a post 30 extending along the axis of rotation and in alignment with a post 31 extending downwardly through the 5 spout driving sleeve 19. The post 30 is non-rotatably secured with the auxiliary ladle but mounted rotatably relative to the ladle unit. Jaw clutch members indicated at 32 are provided on the adjacent ends of the posts 30 and 31 to 10 provide angular adjustment of the post 30 and hence of the ladle 24, by adjustment of the post 31, and yet to permit separation between the posts when the main ladle A is raised.

For rotational indexing adjustment of the post 15 31, cam means are provided at its lower extremity, which is below the gears 21 and here indicated as a sleeve 33 secured upon the post 31 and having a helical cam groove 34. A member 35 cooperative with the cam 34 is provided upon 20 a sleeve 36 fitting about the sleeve 33 and arranged for longitudinal adjustment as by the actuating cylinder 37, and prevented from rotational adjustment relative to the sleeve 19 as by the key 38, a thrust bearing indicated at 39 being 25 provided between the piston of the cylinder 37 and the sleeve 36. Thus the sleeve 36 may have only longitudinal adjustment relative to the sleeve 19, the sleeve 33 may have only rotational adjustment relative to sleeve 19 and post 31, and 30 the longitudinal motion of the sleeve 36 is converted into rotational motion of the post 31.

The proportion and arrangement of the parts is such that a working stroke from the cylinder 37, which is under the control of the operator, 35 will act through the described cam arranged to adjust the auxiliary ladle 24 about the axis of rotation through an angle equal to the unit angular spacing between the nozzle means—180° in the illustrated arrangement where two nozzles 40 are employed. Adjustment of the auxiliary ladle 40 is relative to the spouts and independent of the rotation of the latter and may be made during such rotation.

The auxiliary ladle 24 is provided with a plurality of discharge openings 40 spaced about the axis of rotation correspondingly with the base parts 14 of the spouts. The teeth 32 are so arranged that when they are interengaged in the driving or pouring relation of the parts, the 50 auxiliary ladle will be so indexed that each of its openings 40 will be above the base part 14 of one of the spouts, as indicated in broken lines, Fig. 2, so as to discharge into the latter, the cam means at 34 having been adjusted by the cylinder 37 to one end of its stroke. Obviously therefore adjustment of the cam means to the opposite end of its stroke will reindeer the auxiliary ladle, shifting each of its openings 40 relative to the spouts, although the latter be rotating, so that each opening 40 will thereupon discharge into the base part 14 of another spout. In the example illustrated where two spouts are employed, the two openings 40 will simply be reversed by such adjustment.

65 Operation will be as follows. Assuming the main ladle A being lowered toward the pouring position indicated in Fig. 1, the head 20 being stationary, as the spout unit and auxiliary ladle reach their driving parts 20 and 31, they will rest 70 upon the latter, instead of having support from the ladle bracket means 25. Drive is then commenced through the gears 21 causing substantially immediate engagement for rotational drive of both the spout unit and the auxiliary ladle, by 75

engagement at the teeth 23 and 32 respectively. As the spout unit comes up to speed, the spouts will automatically swing outwardly to the pouring position indicated, under centrifugal force. The mold being meanwhile driven at casting speed, the usual stopper in the main ladle A is withdrawn so that the pouring is commenced from the main ladle into the auxiliary ladle, which in turn discharges through the openings 40 into both spouts simultaneously. The spouts deliver directly to their mold cavities 6 and 7. After the mold cavities are half filled with the molten metal, at the period determined either by pouring time, loss of weight in the main ladle or observation, the operator actuates the cylinder 31 to shift the auxiliary ladle 24, reversing the relation between auxiliary ladle and spouts. Pouring being meanwhile continued, the main ladle outlet is replugged after the mold is filled. By such adjustment of the auxiliary ladle, should one of its openings 40 be greater than another as will usually be the case, nevertheless both mold cavities are equally filled since each discharge opening is equally effective upon each mold cavity during the pouring period.

After pouring is completed the drive is cut off from the spout unit, which quickly slows down and the spouts automatically swing inwardly under the action of gravity, their nozzles clearing the mold. The mold itself may be continued to be driven or its speed even increased. After the spouts have moved to withdrawn position, the main ladle A may be raised, carrying the spouts and auxiliary ladle with it, and moved by any suitable means to fill the mold of the next casting machine, the capacity of the main ladle being preferably much greater than that of any of the casting machines, as will be appreciated by one familiar with the art. Since the single auxiliary ladle and set of spouts move with the main ladle which may be shifted in a relatively short time, there is little heat loss at the spouts.

As the castings cool and shrink in cooling, the mold sections are permitted controlled separation through the mechanism including that indicated at 11 and more fully described in my said copending application.

After the castings in the mold have solidified, the main and auxiliary ladles and the spouts having been meanwhile removed, drive is cut off from the mold, and after the latter becomes stationary and the clamps 9 are released, the entire mold with its castings is removed from the supporting table 1 and thereafter the mold sections are separated and the castings removed therefrom, these operations being performed as by a travelling crane such as that indicated in Fig. 5. By the same crane the emptied mold sections may be immediately reassembled on the casting machine, which is then ready for the next pouring operation. The main ladle, having meanwhile been pouring at another or other casting machines, may then repour at the first casting machine.

With reference now to the modification of Figs. 4 and 6, the arrangement will be as in the modification just described with the exceptions hereinafter noted.

The mold cavity here employed has a different sectional characteristic. The annular port of the cavity opens directly inwardly towards the axis of rotation, thus extending generally in a transverse plane. The walls of the port are protected by hollow, ribbed, generally segmental castings 41 of heat-resisting metal indicated in

Fig. 6, providing air or other insulation, the mold sections being cut away as indicated at 42 to provide additional spaces for the same purpose. The castings 41 are removably mounted upon their mold sections as by bolts 43 and pins 44. The purpose is to retain heat in the gate portion of the castings so far as possible and to increase mold life.

The modified mold of Fig. 6 is substantially octagonal in section, and for many reasons I prefer this form. The mold sections shown here and other sections, shown in my copending application first referred to, are characterized in that, with substantially uniform delivery of metal to the mold sections, annular layers of varying thickness are deposited with advantageous results. The first layer deposited between the outer wall and say, line W, Fig. 6, will lie in a restricted portion of the mold thus giving a layer of sufficient depth to hold its heat and avoid the formation of an oxidized skin at its free surface. Subsequent layers at wider portions of the mold may be of less thickness, as that indicated between lines X and Y, without harmful effect as a large body of metal has been built up for the retention of heat. The final layer deposited adjacent the port or mouth of the mold cavity, as represented by line Z, will be thicker because of reduction in mold section at that point. This provides a comparatively large body of hot metal which will retain its fluidity longer, thus permitting gases and occluded material an easier escape and providing a body of fluid metal to fill any interior cavities which may form on cooling.

The mold section of Fig. 12 permits molten metal to be poured into the port 12 to the level of the dash-dot line. This metal later acts as a riser or feeder for the mold cavity which may cause the metal to recede to the broken line as indicated. This form of mold is useful if the mold cavity is filled while stationary or rotating slowly. Later when the metal is near its solidification point or even partly solidified the mold may be rotated at a higher rate of speed to force the excess metal toward the mold cavity. I find that by thus relying partly upon the natural cooling or solidification of the metal and partly upon varying the centrifugal force applied to various annular layers of the casting. I am able to control the density and structure of the metal within wide limits.

Otherwise the arrangement of mold sections, their mounting on the table 1 and its drive by the gears 2, is as before. The assembly of the nozzles 45, movably upon the member 17' to form a unit therewith, which unit is removably supported in driving relation with a head 20 driven by gears 21, is also as before.

The auxiliary ladle or tundish 46 is, however, differently mounted. It is tiltable about a horizontal supporting axis offset from the center of rotation as at 47. Tilting adjustment of the auxiliary ladle is had by a central push rod 48 mounted in the member 17' for sliding adjustment along the axis of rotation, and in alignment with a push rod 49 extending downwardly through the mold and spout driving apparatus to a connection with suitable means generally indicated at 50, by which the operator may cause vertical adjustment. Obviously such adjustment controls tilting of the tundish 46 about its tilting axis 47. The tundish is provided with a pair of openings 51, one for each spout disposed on a line which is perpendicular to the axis 47. By the arrangement here described and illustrated, it

- will be apparent that the tundish has no adjustment about the axis of rotation but it will be equally obvious that by its described tilting adjustment, the relative head upon the two discharge openings 51 may be varied by vertical adjustment of the push rod 48; so that the discharge may be apportioned and equalized between the two spouts 45 although the two openings 51 may not be of identical size.
- 10 That the nozzle and tundish assembly may be removable from the casting machine as a unit, the part 17' which interrelates these elements is provided with suitable means by which it may be raised. Such means are here shown in the form 15 of a pair of oppositely extending lugs 52.

A general layout appropriate for this form of machine, appears in Fig. 5. The main ladle A1 is carried upon a suitable car 53 which may be a scale car and is mounted upon rails to move along 20 a row of casting machines, two of which are here illustrated. A small trolley car 54 is provided upon rail means extending between the rails for the car 53 and has elevating hook means 55 adapted to engage the lugs 52 of the spout assembly. The ladle car 53 and trolley car 54 are preferably so arranged that the trolley car may run under the rail car. In operation the function of 25 the trolley 54 is to shift the spout unit between casting machines while of course the ladle car 53 correspondingly shifts the ladle A1. Thus as 30 before, although by a different arrangement, a single spout unit serves all of the casting machines of the row, as does the ladle A1.

While there may be a greater number of casting 25 machines in the row indicated in Fig. 5, disposed transversely of the view, it is preferable that but two casting machines be served by the crane as indicated. This crane has preferably three hooks 56 for conveniently engaging the mold sections 40 for removing them from the casting machines, is shiftable laterally between its two machines, and is arranged to travel longitudinally so that it may deposit the mold sections, separate them and remove the castings therefrom at locations rearward or forward of the plane of Fig. 5.

While centrifugal casting of course produces improved density with great tendency to segregate occlusions, impurities and the like, into a scrap crop zone at the inner radius of the casting, an 50 object of this invention is to improve this separating action. Since the density of the radially outermost metal, is increased by the weight of the innermost metal, and the outermost metal being poured first has a tendency to solidify first, 55 I provide means tending nevertheless to increase density at the radially innermost part of the casting.

Such means comprise as indicated in Figs. 6 and 7, a pair of pressure rollers 57, one for each 60 mold cavity and equally spaced about the axis of rotation, in staggered relation with the spouts 45. These rollers are adapted each to enter the port of its mold cavity after completion of the pouring operation, and while the metal at the inner radius 65 retains some plasticity. Each roller 57 is mounted as upon a lever 58 for radial adjustment into and from its port, and has associated actuating means such as a cylinder 59 for such adjustment and for providing substantial bearing of the rolls 70 against their castings. The pressure roller assembly need not be removable from the casting machine with the spout assembly, and instead is preferably secured with the spout driving head 28 for rotation with the latter as by the bracket 64. 75 The cylinders 59 are preferably actuated by oil

or the like, conducted to them through suitable ducts 60 in the machine, a stuffing box 61 providing communication with the pressure and relief lines 62 and 63 which are of course under the control of the operator.

In operation, after pouring of the castings and usually after removal of the spout unit, the pressure roll unit is brought to a desired speed by the drive through the gears 21 and pressure admitted to the cylinders 59 to cause bearing of the rollers 58 against the casting as indicated in Figs. 6 and 7. During this operation the pressure unit may preferably operate in the direction of the mold but at somewhat less speed. The pressure rollers thus travel along the ports of the mold cavities 10 at a relatively slow speed, bearing against the inner circumferential face of the contents thereof. Thus the metal on the inner radius of the casting is compacted and impurities removed therefrom radially inwardly by a squeezing action. 15 The casting metal on the inner periphery being somewhat more plastic than the metal further removed radially, its density is materially increased by the squeezing action, which has little or no effect upon the metal at the outer periphery 20 of the casting.

After the squeezing operation and before the mold is removed from the casting machine, the pressure rolls are withdrawn radially inwardly by their cylinders 59 to clear the mold sections. 25

With reference now to Fig. 8, another spout arrangement is indicated. In this arrangement the base part 70 of one spout is arranged to form a cavity annular about the axis of rotation as indicated, from which the trough part 71 of the spout leads laterally. The base part 72 of the other spout is arranged beneath a central through opening in the spout 70, to receive a stream from a central outlet 73 in the ladle A2. This ladle, which may be the main ladle, is provided with another outlet 74, offset from the axis of rotation of the casting machine, to deliver into the annular cavity of the upper spout.

Obviously, when pouring is had from the ladle as indicated, simultaneously through both outlets 45 73 and 74, each will deliver into the base cavity of one of the spouts although the ladle A2 be stationary and the two spouts be rotating as a unit.

That turbulence be reduced and splash prevented, each spout is provided with an obstruction 75 effective as a dam between the cavity of the base part, and the trough. By such obstruction sufficient volume of the molten metal is retained in the base cavities of the spouts, into which the streams from the ladle deliver, to prevent splashing of the latter.

With reference now to the modifications of Figs. 9 to 11, the main ladle A3 is provided with a pair of outlets 76 equally spaced from the axis of rotation of the casting machine. Two spouts are indicated having their base parts 77 so related that together they will always receive the discharge from both ladle outlets 76, as indicated in Fig. 10. The base part of one of the spouts is slightly lower than that of the other, so that the lower spout may be arranged to discharge into the lower mold cavity generally as indicated in Figs. 1 and 4. The upper spout has a lip part 78 overhanging the adjacent edge of the lower spout so that the streams from the ladle cannot overflow between the spouts, each spout has a trough part 79 leading generally radially from the axis of rotation, substantially as before.

For each spout, means are provided for ob-

structing flow from its base cavity to its trough, generally as indicated at 80. In each of these obstructions 80, however, is an opening 81, preferably as of V form as indicated in Fig. 10, extending downwardly to the lowermost level of the base cavity and with sides diverging upwardly. By this arrangement, when pouring commences from the ladle, a head of molten metal will be quickly built up in the base cavities of the spouts 10 so that the ladle streams will deliver into the retained pools with minimized splash; the proportions of the openings 81 relative to the ladle discharge openings, being arranged for the purpose, yet to permit outflow through the spout troughs 15 equal to the discharge from the ladle, once sufficient volume has been built up in the spout bases.

On the other hand, since the opening 81 extends to the lowermost level of the base cavities, after pouring from the ladle has ceased, the base cavities 20 will be emptied by way of the openings 81.

In this arrangement it will be apparent that during rotation of the spouts in the operation of the machine, each will deliver equally regardless of absolute equalization of discharge between the ladle outlets; since each outlet has delivery alternately to the two spouts as the latter rotate. It will be equally apparent that with this arrangement but one outlet might be provided in the main ladle, or more than the two illustrated, with the same equalization result provided 30 the outlets have offset relation from the center of rotation.

It will be apparent that numerous combinations, not specifically illustrated, may be formed from the above elements. For example, a tundish might be employed to be effective between the main ladle and spout means in the arrangement of either Fig. 8 or that of Figs. 9 to 11; the tundish performing the function of receiving a single stream from the main ladle, with minimum turbulence or splash therefrom, and distributing the molten metal so received, to the spouts in separate streams, one for each. The form of spout illustrated in Figs. 9 to 11, could be employed in place of those illustrated in Figs. 1 and 2. The opening 81 in the obstruction 80 appearing in Fig. 10, could be employed in the obstruction of Fig. 8. Also, as will be appreciated, whether the main ladle has one or more outlets, the usual 45 stopper means will be provided for controlling ladle discharge at the will of the operator.

What I claim is:

1. In a casting machine of the class described and having ladle means and a plurality of rotatably mounted spouts arranged to simultaneously receive delivery therefrom, said ladle means having a corresponding plurality of outlets for the purpose, means for equalizing the rate of delivery among said spouts and comprising means providing for adjustment of said ladle means about an axis and relative to said spouts and during spout rotation.

2. In a machine of the class described, rotatably mounted mold means arranged to provide a pair of longitudinally spaced cavities, ladle means and a pair of spouts arranged to simultaneously receive delivery therefrom while rotating, each to deliver to one of said cavities, said ladle means having a corresponding pair of outlets for the purpose, means for equalizing the rate of delivery between said spouts and comprising means providing for adjustment of said ladle means about an axis and relative to said spouts and during rotation of said spouts, where-

by said mold cavities may be uniformly and simultaneously filled.

3. In a casting machine of the class described and having an auxiliary ladle and a plurality of spouts mounted for rotation about an upright axis and arranged to simultaneously receive delivery therefrom while rotating, said ladle having a corresponding plurality of outlets for the purpose, said ladle being removably mounted relative to other parts of said machine and said machine having means for rotatably driving said ladle coaxially with said spouts when the ladle is mounted, means for equalizing the rate of delivery among said spouts and comprising means providing for adjustment of said ladle about said axis relative to said spouts during rotation of said ladle and spouts.

4. In a casting machine of the class described and having an auxiliary ladle and a plurality of spouts arranged to simultaneously receive delivery therefrom, said ladle having a corresponding plurality of outlets for the purpose, means for equalizing the rate of delivery among said spouts and comprising means providing for adjustment of said ladle relative thereto about an upright axis, said ladle being removably mounted relative to other parts of said machine and said spouts being associated with said ladle for removal therewith as a unit, said machine having means for rotatably driving said unit when mounted.

5. In a casting machine of the class described and having a rotating auxiliary ladle and a pair of spouts arranged to simultaneously receive delivery therefrom during rotation thereof, said ladle having a corresponding pair of outlets for the purpose, means for controlling the relative rate of delivery between said spouts and comprising means providing for tilting adjustment of said ladle during said rotation, about an axis disposed to cause relative variation in flow from said outlets to follow said adjustment.

6. In a casting machine of the class described and having a ladle and a plurality of spouts disposed in spaced relation about an upright axis, said ladle having an outlet offset from said axis, each spout having a base part similarly offset from said axis and adapted to receive delivery from said outlet, the arrangement being such that among the combined base parts of all of said spouts, said ladle outlet will deliver successively into said spout base parts and always into one or another thereof, as motion is had, about said axis, between said ladle and all of said spouts as a unit, means for providing said motion, mold means having a plurality of cavities disposed concentrically of said axis in spaced relation longitudinally thereof, each spout being arranged to deliver to one of said cavities.

7. In a casting machine of the class described and having an auxiliary ladle and a plurality of spouts disposed in equally spaced relation, about an upright axis, to simultaneously receive delivery from said ladle, said ladle having a corresponding plurality of similarly disposed outlets for the purpose, means for controlling the relative rate of delivery among said spouts and comprising means providing for adjustment between said ladle and said spouts about said axis through an angle to change the spout receiving delivery from each outlet.

8. In a casting machine of the class described and having an auxiliary ladle and a pair of spouts arranged to simultaneously receive delivery therefrom, said ladle having a corresponding pair of

- outlets for the purpose, means for rotation of said ladle and spouts about an upright axis during said delivery, and means for equalizing the rate of delivery between said spouts and comprising 5 means providing for adjustment between said ladle and said spouts, during said rotation and about said axis thereof, to reverse the spouts into which said outlets deliver.
9. Apparatus of the class described comprising 10 a ladle and cooperative spout, said ladle having a gravity discharge opening, said spout having a base part disposed beneath said ladle opening and spaced therefrom to receive a stream from said ladle, and having a trough part leading laterally therefrom, dam means, between said 15 base and trough parts of said spout and having a passage opening of size increasing upwardly, the parts being so proportioned and arranged that during discharge from said ladle, said dam 20 means will retain in the base part of said spout sufficient fluid metal to prevent splash therefrom, and after said pouring said opening will drain said base part.
10. In apparatus of the class described, a pair 25 of spouts mounted for rotation about an upright axis and for adjustment transverse of said axis to and from a pouring position, said spouts having adjacent base parts and each having a trough part leading laterally from its base part, a ladle 30 having a pair of outlets each disposed to discharge into one of said spout base parts, the base part of one of said spouts having a lip extending transversely of said axis and overlying the adjacent side wall of the base part of the other 35 spout.
11. In a machine for centrifugally casting steel 40 ingots or the like, a rotatably mounted mold arranged to provide a cavity concentric about the axis of mold rotation, with a restricted annular port part directed toward said axis, means for
- pouring into said mold, and means arranged to apply pressure radially outwardly of said axis, against the port contents, and progressively therealong.
12. In a machine for centrifugally casting steel 5 ingots or the like, a rotatably mounted mold arranged to provide a major cavity concentric about the axis of mold rotation, with an annular port of width lengthwise of said axis substantially less than said cavity, means for pouring into said 10 mold, and means movable in said port and adapted to apply pressure, radially outwardly of said axis, against the port contents, whereby the major cavity contents may be subjected to pressure hydrostatically increased by the relative narrowness 15 of said port.
13. In a machine for centrifugally casting steel 20 ingots or the like, mold means mounted for rotation about an upright axis, and having a major cavity concentric about said axis and a restricted 25 annular port leading to the upper and radially innermost portion of said major cavity, means for driving said mold means, and nozzle means arranged to deliver to a circumferentially restricted section of said port.
14. In a machine for centrifugally casting steel 30 ingots or the like, mold means mounted for rotation about an upright axis, and having a major cavity concentric about said axis and a restricted 35 annular port of substantial length leading slopingly downwardly and radially outwardly to the upper and radially innermost portion of said major cavity, means for driving said mold means, whereby, after pouring, centrifugal forces upon the contents of said port may be substantially enhanced by gravitational forces thereupon, and the major cavity contents may have maximum hydrostatic pressure from the port contents.
